UNITED STATES PATENT OFFICE

BROR GUSTAF NORBERG, OF SEATTLE, WASHINGTON

DESIGN FOR A COMBINATION CURTAIN POLE, CURTAIN-ROD BRACKET, AND SUSPENDING MEANS

Application filed July 26, 1929. Serial No. 32,215. Term of patent 3½ years.

To all whom it may concern:

Be it known that I, BROR GUSTAF NORBERG, residing at Seattle, in the county of King and State of Washington, have invented a new, original, and ornamental Design for a Combination Curtain Pole, Curtain-Rod Bracket, and Suspending Means, of which the following is a specification, reference being had to the accompanying drawing, forming part thereof.

Figure 1 is a perspective view of a combination curtain pole, curtain rod bracket, and suspending means, showing my new design;

Fig. 2 is an end elevation thereof.

I claim:

The ornamental design for a combination curtain pole, curtain rod bracket, and suspending means, as shown.

BROR GUSTAF NORBERG.
